(57) **CLAIM**

The ornamental design for a display screen or portion thereof
with graphical user interface, as shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a front view of a display screen or portion thereof
with graphical user interface showing our new design; and,
FIG. 2 is a front view of a second embodiment thereof.

The broken lines showing the display screen or portion
thereof form no part of the claimed design.
